AUTOMATIC SCRAPER FOR STRIP METAL STOCK

Fred H. Naish, Birmingham, Ala., assignor to Connors Steel Company, a corporation of Delaware

Application June 28, 1937, Serial No. 150,741

6 Claims. (Cl. 80—1)

My invention relates to an automatic scraper for mills rolling strip stock.

More particularly my invention is applicable to mills of the class suited for the rolling of 5 narrow strip stock, such as hoop stock, in which the strip travels at a high speed in its traverse of the finishing mill pass.

The object of my invention is to reduce to a minimum the amount of finished stock in each 10 piece rolled which gets by the scraper untreated and is therefore unmarketable. It is customary for hoop strip stock to travel through the finishing rolls at a speed equal to, or even in excess of, 1500 feet per minute, or 25 or more feet per 15 second. At such speeds it will be obvious that whatever time interval is permitted to elapse between the moment that the mill rolls grip the forward end of a strip of stock and the setting of the scrapers to engage the stock, will represent a loss. Where it is attempted to set the 20 scraper by hand or stock actuated switch, the delay of a fraction of a second in setting the scraper may mean many feet of untreated stock that must be scraped, while if the scraper is set in advance of the stock's engagement between the rolls, the feed of stock will be stopped, necessitating release of the scraper and causing 25 delay in operation and reduction of output.

The purpose of my present invention is automatically to apply the scraper contemporaneously with the engagement of the forward end of the strip stock between the mill rolls. To this end the scraper is set close as it conveniently may be to the mill rolls on their receiving side and 30 electro-magnetically controlled means are employed to set the scraper to its work responsive to the increase of load coming on the mill when it grips the stock. In other words, the increase 35 of power required to drive the rolls when they take hold of the strip will act automatically and instantaneously to apply the scraper so that the unscraped waste stock on each piece rolled is substantially limited in length to the distance between the scraper and its associated mill pass. 40

45 The discharge of the stock piece from the rolls will likewise effect an automatic resetting of the scraper to open position so as to permit the immediate feed of new stock into the mill.

My invention further comprises the novel details of construction and arrangements of parts which, in their preferred embodiment only, are illustrated in the accompanying drawings with reference to which my invention is more particularly described and claimed.

50 According to the drawings:—

Fig. 1 is an end view of a typical strip rolling mill showing my improved automatic scraper control associated with the mill power circuits laid out in a conventional diagram.

Fig. 2 is a plan view of the mill and scraper mechanism.

Fig. 3 is a cross sectional view showing the scraper elements in operative position.

Fig. 4 is a diagrammatic circuit layout for a load relay suitable for the control of the scraper.

Similar reference numerals refer to similar parts throughout the drawings.

In the embodiment of my invention illustrated, I show a typical mill roll stand comprising a housing 5, the usual bearings 6 and 7 for the 15 upper and lower rolls 8 and 9, and adjusting screws 10 to set the upper roll bearings so as to produce the desired roll clearance. Suitable guides 11 receive the incoming stock and deliver it into the mill pass, while corresponding 20 guides 12 carry the finished stock away from the rolls.

I mount fast on the housing 5, adjacent to the stock guides 11, a stationary scraper frame 13 comprising the spaced scraper bars 14, 15 25 and 16. A vertically movable scraper frame 17 carries scraper bars 18 and 19 which depend below it and in their lowered operating position fit between and coact with, bars 14, 15 and 16 to bend the stock and effectively scrape it on both 30 sides, as will appear in Fig. 3. A frame 20, also attached to the housing 5, supports an upright cylinder 21 centrally over the bar 14. The movable frame 17 has end guide extensions which slide in the grooves 22 formed in the vertical 35 sides of the frame 20. The cylinder has its piston connected centrally to the frame 13 on its mill side and it is adapted to be operated by compressed air supplied from any suitable source, such as the tank 23 from whence it flows through 40 pipe 24 to a four-way valve 25 controlling its flow to, and exhaust from, the cylinder. This valve may be of any standard four-way type and as it forms no particular part of my present invention, it will not be illustrated in detail. 45

The valve body has an exhaust outlet 26 and air lines 27 and 28 leading to the opposite ends of the cylinder 22. The valve element in the form shown is controlled by a reciprocable plunger 29 connected to a lever 30 pivoted at 50 one end to the bracket 31 and at its other end connected to the core 32 of the solenoid 33. As shown, the core passes loosely through the free end of the lever 30 and carries at its lower end a spring seat 34 upon which rests a coiled 55

compression spring 35 that supports the lever 30. The lever 30 is connected by a coil tension spring 36 to a bracket 37 on the valve body and thus the free end of the lever is biased downwardly against spring 35. Assuming the solenoid 33 deenergized, the parts will occupy the position shown in Fig. 1 with the pressure admitted to the lower end of the cylinder through air line 31, and the upper end of the cylinder open to the exhaust through air line 28 and valve outlet 26. The scraper will be in open position and the mill rolls will be turning idle, as indicated by the arrows, ready for the reception of the strip stock to be rolled.

15 The electric motor for driving the mill rolls is omitted but a metering power circuit 40, 41 therefor is shown comprising an ammeter 42, a volt meter 43, and a current load relay 44. This load relay, in the manner well understood 20 in this art, acts to open and close a 110 volt valve control circuit comprising the leads 45 and 46, which include the solenoid 33 and also the double safety switch 47 and the hand operated control switch 48. The load relay is of such 25 character that the solenoid circuit is open when the mill is idling but the moment the stock enters the pass between the mill rolls more power will be required in the primary or load responsive circuit 40, 41 and such increased flow of current 30 will operate the load relay to close the secondary or valve control circuit 45, 46 energizing the solenoid 33, lifting the solenoid core 32 and raising the valve lever 30, against the action of spring 36, to reverse the four-way valve 25 and admit 35 air through the line 28 into the upper end of the cylinder 22 while exhausting air from the lower end of the cylinder through the line 27 and the valve outlet 26. The combined action of air and gravity will thrust the movable scraper element 40 47 quickly downward into its operating position, shown in Fig. 3, and will hold it in this position with its scraper bars interleaved between the blades of the stationary scraper bars so as to effectively scrape and clean the stock passing to 45 the mill pass. As soon as the stock leaves the mill rolls the current load factor in the primary current will drop, causing the load relay to open the secondary or valve control circuit, whereupon the solenoid will be deenergized, and the spring 50 36 will reverse the four-way valve 25 to admit air below the piston in cylinder 22 and exhaust air from above the piston, so that the movable scraper blade 47 is lifted to open the scraper and allow the next stock to pass freely to the entering mill 55 guides 11.

In Fig. 4 I have shown a conventional wiring diagram for the current load relay 44 as this may be of standard design which in various types is available on the market.

60 As illustrated in Fig. 4, the primary circuit leads 40 and 41 are respectively connected to the terminals 50 and 51 of the relay, these terminals being in turn connected to the ends of a circuit 52 which includes coils surrounding a plunger 53, the coils having tap leads to a connector block 54, so that the desired tap values can be obtained for setting the plunger to operate at the desired predetermined load value. This load value is such as will result when the mill rolls bite into the stock, and under such conditions the increased flow of current will lift the plunger and operate the switch arm 55 to close the circuit 56, the sides of which are connected to the terminals 57 and 58, 65 to which respectively the control circuit leads 45

and 46 are connected. Thus a current flow greater than that required to drive the mill when idling will instantly lift the switch arm 55 and close the valve control secondary circuit energizing the solenoid 33 and causing the air motor, assisted by gravity, to thrust the movable scraper frame 17 into quick engagement with the stock. In like manner, the moment the mill rolls release the stock, the load factor on the primary circuit drops, the plunger 53 is lowered, the switch 55 is opened and the secondary circuit is broken, whereupon spring 36 resets the valve to the position shown in Fig. 1 and the air pressure lifts the scraper frame 17 so that the new stock is ready to be introduced into the mill.

15 The switches 47 and 48 are normally closed when the apparatus is in operation and are not open as shown in Fig. 1. The switch 48, a manually controlled switch of any suitable and convenient type, is arranged so that the operator can 20 at will open the valve controlling circuit. Thus, when the mill is starting up and the load factor will be high, it is necessary to hold switch 48 open until the mill attains idling speed, then it can be closed and the current relay 44 will thereafter 25 automatically control it. Likewise, if anything goes wrong during the rolling operation, the stripper can be immediately disengaged from the stock by opening switch 48. Switch 47 is purely a 30 safety switch.

35 While I have shown my invention in but one form, it will be obvious to those skilled in the art that it is not so limited, but is susceptible to various changes and modifications, without departing from the spirit thereof, and I desire, therefore, that only such limitations shall be placed thereupon as are imposed by the prior art or as are specifically set forth in the appended claims.

40 What I claim as new and desire to secure by Letters Patent, is:

1. The combination with a mill for rolling strip stock of an automatic scraper mounted adjacent to and on the receiving side of the mill, an electrical power circuit for the mill drive comprising a load relay, a secondary circuit controlled by 45 said load relay responsive to the presence or absence of stock between the mill rolls, an electro-magnetically controlled valve means responsive to said secondary circuit, and fluid pressure means controlled by said valve means and adapted to 50 apply the scraper to strip stock entering the mill pass and to set the scraper for admission of fresh stock to the mill, and a load relay in the mill drive circuit adapted to control the secondary circuit and set the scraper in operating position 55 as soon as the stock enters, and during its traverse of, the mill roll pass.

2. The combination with a mill for rolling strip stock, a scraper mounted close to the receiving side of the mill and comprising cooperating stationary and movable elements, a fluid pressure motor to open and close the scraper elements, a control valve for said motor, electro-magnetic means to operate said valve to reverse said motor, an electric supply circuit for the mill drive, a 65 load relay responsive to the circuit flow in said circuit, and a secondary circuit including said electro-magnetic means and controlled by said load relay to reverse said motor when stock enters and leaves the pass between the mill rolls.

3. A scraper means for a rolling mill, according to claim 1, in which the electro-magnetically controlled valve means comprises a valve operating lever, spring means normally holding the lever in position to render the scraper inoperative, and 75

a solenoid adapted to move the lever and valve against said spring to set the scraper in operative engagement with the stock.

4. A scraper means for a rolling mill, according to claim 2, in which the secondary circuit comprises a manually controlled switch operable to open and close the scraper elements independently of the operation of said load relay.

5. The combination with a rolling mill having an electrical power circuit carrying current for the drive of the mill rolls, a scraper means adapted to act on the stock in its passage to the mill and comprising separable elements operable to engage and release the stock, electro-magnetically controlled means to effect the engagement and disengagement of said scraper elements, and means, automatically responsive to an abnormal current flow in the mill power circuit responsive to the engagement of stock between the mill rolls, 10 for effecting automatically engagement of the scraper elements with the stock as soon as it is grasped by the rolling mill rolls.

6. The combination with a rolling mill having an electrical power circuit carrying current for the drive of the mill rolls, a scraper adapted to act on the stock in its passage to the mill, an electro-magnetically controlled means, automatically responsive to an abnormal current flow in the mill power circuit responsive to the engagement of stock between the mill rolls, to cause the scraper to engage the stock as soon as it is grasped by the rolling mill, said means comprising a relay 15 responsive to the current flow in the mill drive power circuit, a relay operated switch means operable responsive to a predetermined current flow in said circuit, a secondary circuit controlled by said switch and comprising an electro-magnetically operated valve, and a fluid power motor controlled by said valve and adapted according to its setting to cause the scraper to engage or release the stock. 20
